UNITED STATES PATENT OFFICE.

ELMER H. LORING, OF WORCESTER, MASSACHUSETTS, ASSIGNOR TO THE
LORING & BLAKE ORGAN COMPANY, OF SAME PLACE.

ORGAN-CASE.

SPECIFICATION forming part of Letters Patent No. 349,656, dated September 21, 1886.

Application filed June 14, 1886. Serial No. 205,089. (No model.)

To all whom it may concern:

Be it known that I, ELMER H. LORING, a citizen of the United States, residing at Worcester, in the county of Worcester and State of Massachusetts, have invented certain new and useful Improvements in Pedal-Cover-Operating Mechanism, of which the following, together with the accompanying drawings, is a specification sufficiently full, clear, and exact 5 to enable persons skilled in the art to which this invention appertains to make and use the same.

The object of this my present invention is to provide a simple and efficient connection, 15 whereby the pedal-cover in an organ-case can be automatically operated by movement of the fall, said connecting mechanism being such that it can be economically manufactured and conveniently arranged in the organ-case without interfering with other parts of the organ action; also to provide a fall-swing of peculiar 20 form which will not interfere with the end of the brace where it meets the side of the case. These objects I attain by mechanism, the nature of which is herein shown and described.

In the drawings, Figure 1 is a sectional view showing the arrangement of my improved pedal-cover-operating mechanism within the organ-case. Fig. 2 is a horizontal section of the same. 30 Fig. 3 is a vertical section through the sheaves and bracket at the side of the pedal-space, and Fig. 4 is a longitudinal section through the axis at one end of the pedal-cover roll.

In referring to parts, A indicates the organ-case, of usual form, with brackets or pilasters 35 *a* on the front, at the sides of the pedal-space. B indicates the pedals; C, the action; E, the brace, which extends from end to end of the case, and F the fall or cover which closes and 40 opens the manual, all of which parts may be of ordinary or any suitable construction. The fall F is hinged to the fall-swing D, which latter I make in a curved form, as shown in Fig. 1, and with an offset, as at *d*, so that the lower 45 part of the curve is at some distance back from the pivot *e*, whereon the swing-arm D is pivoted to the end of the case. By making the fall-swing in the offset and curved form shown, the interference thereof with the end of the 50 brace E, where it is attached to the end of the case, is avoided, and the necessity of cutting

into the brace to form space therefor, and thus weaken the stock of the brace, is obviated.

H indicates the pedal-cover, connected with a roll, *h*, the ends of which are supported in 55 the brackets *a*, so as to form a hinge on which the cover H swings up and down when opening and closing the space in front of the pedals B. Upon the end of the roll *h*, I attach a sheave, I, which is preferably located within a mortise, 60 *a'*, formed in one of the brackets, *a*. Along the interior of the case I arrange a shaft or rod, K, rotatable in suitable bearings, *l*, and provided at one end with a sheave, J, and at the opposite end with a crank, K', substantially as 65 shown in Fig. 2. A band, *m*, connects the sheaves I and J. (See Fig. 3.) Said band is fixed to the periphery of the sheaves with a suitable fastening device, as at *n*, so that when the sheave J is turned the sheave I will also 70 be turned, and the roll *h* and cover H will be thereby operated. A rod or bar, P, connects the crank K' with the fall-swing D, in the manner illustrated by Fig. 1. Said rod is in the present instance made in two parts, with a 75 right and left screw-threaded adjusting-sleeve, *r*, for shortening or elongating its length; but, if preferred, it might be made without means of adjustment.

The operation is as indicated by dotted lines 80 in Fig. 1. When the fall F is raised and slipped back into the case for opening the manual, the backward and forward movement of the curved or offset portion of the fall-swing, to which the rod P is pivoted, depresses the crank K' by 85 means of the rod P, thereby effecting partial rotation of the shaft K and sheave J, which, by means of the band *m*, operates the roll *h* to swing the cover H to its elevated position, as 90 will be readily understood from the inspection of drawings.

In some instances, in lieu of connecting sheaves J and I by means of the band *m*, it may be desirable to make the connection by means of spur-gears—that is, the wheels I J, being 95 provided with teeth, and an intermediate toothed wheel being arranged between them for connecting and transmitting the motion from the shaft K to the roll *h*.

The advantages of my invention are that the 100 mechanism can be manufactured at a comparatively small cost, conveniently applied to use,

and does not interfere in any manner with the ordinary construction and arrangement of the organ actions.

I am aware that means for automatically operating a pedal-cover in connection with the fall has been heretofore employed in an organ-case, and I do not therefore herein make claim, broadly, to such feature. So far as I am aware, however, the mechanism for effecting such operation is of an essentially different nature from that herein described.

What I claim as of my invention, and desire to secure by Letters Patent, is—

1. The fall-swing arm curved and offset in the manner set forth, in combination with the brace and fall in an organ-case, as and for the purpose specified.

2. A pedal-cover mechanism consisting of the cover H, having a hinging-roll, h, at its edge, provided with a wheel fixed thereto, in combination with a rotative operating-shaft,

K, provided with a wheel, J, and devices for connecting and transmitting motion between said wheels, whereby rotation of said shaft effects the elevation or depression of said cover, substantially as set forth. 25

3. The combination of the fall F, the fall-swing D, the crank-shaft K, supported in bearings on the case and provided with a sheave, J, the rod P, connecting the fall-swing and the crank K' on said shaft, the pedal-cover H, provided with a sheave, I, axially coincident with the hinging of said cover, and a band, m, connecting said sheave with the sheave on said crank-shaft, substantially as and for the purpose set forth. 30 35

Witness my hand this 10th day of June, A. D. 1886.

ELMER H. LORING.
